UNITED STATES PATENT OFFICE.

WILLIAM M. REICHART, OF CLEVELAND, OHIO, ASSIGNOR TO THE CHANDLER AND PRICE COMPANY, OF CLEVELAND, OHIO, A CORPORATION OF OHIO.

SAFETY DEVICE FOR PLATEN-PRESSES.

1,192,118.

Specification of Letters Patent. Patented July 25, 1916.

Application filed March 12, 1915. Serial No. 13,925.

To all whom it may concern:

Be it known that I, WILLIAM M. REICHART, a citizen of the United States, and a resident of Cleveland, county of Cuyahoga, 5 and State of Ohio, have invented a new and useful Improvement in Safety Devices for Platen-Presses and the like, of which the following is a specification, the principle of the invention being herein explained and the 10 best mode in which I have contemplated applying that principle, so as to distinguish it from other inventions.

The subject of the present invention is a safety device for platen printing presses, or 15 a similar machine having relatively movable jaws or members.

In platen printing presses the placing of the sheets upon the platen, and the proper positioning of the same, has caused a number of accidents, since the operator, after 20 first placing a sheet thereon, may notice, as the platen moves forward, that the sheet is not properly positioned, and will many times attempt to change the position of the 25 sheet during the movement of the platen. To do this he is obliged to interpose his hands between the platen and the bed, from which position he is unable, many times, to remove them in time to prevent crushing by 30 the two members of the press.

The present invention provides an automatically operative means for moving the hands or arms of the operator from between the platen and bed if they happen to be left 35 in that position too long, that is until they are in danger of being caught. At the same time, the device is designed so as not to interfere with freedom of access to the space in question, to adjust the sheet in the platen, 40 before the parts of the machine close sufficiently to endanger such operator. Particularly in the case of the platen printing press, it is desirable to leave the operator free to manipulate the sheet until the grippers on 45 the platen take hold, and since the bed does not come into dangerous proximity to said platen until this stage in the operation of the press is reached, I provide for the retarded action of the safety device, as will be later 50 explained in detail.

While for purposes of illustration, the device has been herein shown and described solely in connection with a platen printing

press, its value in other similar connections and its adaptability thereto will be readily 55 evident to those skilled in the various arts.

To the accomplishment of the foregoing and related ends, said invention, then, consists of the means hereinafter fully described and particularly pointed out in the claims. 60

The annexed drawings and the following description set forth in detail certain mechanism embodying the invention, such disclosed means constituting, however, but one of various mechanical forms in which the 65 principle of the invention may be used.

In said annexed drawings: Figure 1 is a side elevation partially illustrating the press, together with one form of my improved device; Fig. 2 is a view similar to Fig. 1, but 70 showing only that part of the press to which the device is attached, and illustrating the latter in its operative position; Fig. 3 is a rear elevation of the safety device, looking from the right of Fig. 2; Fig. 4 is a side elevation similar to Fig. 1, but illustrating a modification of the actuating means for the device; Fig. 5 is another side elevation showing the construction shown in Fig. 4 in its operative position; and Fig. 6 is a sectional 75 detail, as indicated by the line 6—6, Fig. 5.

Referring, first of all, to the form of construction illustrated in Figs. 1, 2 and 3 more especially, the same is shown as attached to a platen printing press of more or less 85 familiar construction, including the main frame 1, a movable platen 2, and a pivoted arm or bed 3 which carries the form. The construction and mode of operation of this type of printing press being well known, it 90 is not necessary to describe the arrangement and operation of any other parts of the press than those just referred to, since they are not concerned with the present invention. As to the parts in question, it is sufficient to state that in the operation of the press the platen 2 is moved forward, that is to the left, from the position shown in Fig. 1, to the position shown in Fig. 2, and simultaneously the bed 3 is actuated to meet the 100 platen as illustrated in the last named figure, such movement of the bed, however, being completed only after the platen has come to rest. Pivotaly attached to the lower edge of the latter are gripping bars or fingers 2^a 105 which are suitably actuated, as the platen is

thus moved into operative position, to close back against the same and thus hold in place the inserted sheet designed to receive the impression from the form that is carried by the bed. Since these fingers when thus closed prevent further adjustment of the sheet, the operator should remove his hand from between the platen and bed when the former is brought into its full operative position, and the safety device of present interest is designed to insure such removal as has already been explained, and to prevent the insertion of the hand, once this stage in the operation is reached, for the bed thereupon closes in 15 promptly and a serious injury to the operator is apt to result.

The principal element of my improved device is a guard frame 4, which is preferably of the rectangular form illustrated in 20 Fig. 3, and which preferably bears an imperforate screen 5 of canvas or other material, stretched more or less tautly from one side member to the other. This frame is pivotally attached to the ends of two similar 25 arms 6 projecting radially from a rock shaft 7 that is in turn journaled in suitable bearings provided in a frame 8. The latter may be an integral part of the platen or platen support if desired, or may be made as a 30 separate member adapted to be detachably secured thereon by means of clamps 9, thus adapting the device for attachment to printing presses already in use. The pivotal axis of the frame is not only eccentric of the 35 shaft's axis but lies nearer one side than the other of such frame, and a link 10 connects such adjacent side with a fixed arm 11 on the frame 8, so that as the shaft 7 is rocked, an oscillatory or swinging movement will 40 be imparted to said frame about such pivotal axis in addition to the bodily movement thereof as it is carried upwardly by the arms 6. The result of this arrangement is to fold said frame, with the screen carried thereby, entirely back and behind the 45 platen in the inoperative position of the latter illustrated in Fig. 1, or to raise such frame and screen into the outstanding position 50 illustrated in Fig. 2 in the operative position of said platen, it being understood that the rock-shaft is oscillated in the proper direction at the proper time to thus correlate the position of the frame with the position of the platen.

55 The shaft 7 is normally rocked to retain the frame in its folded condition by means of a coil spring 12 surrounding said shaft at one end and having its one end attached to the frame 8 and its other end attached 60 to the adjacent arm 6. Said shaft 7 is adapted to be rocked in the opposite direction so as to move the frame 8 into its outstanding position by means of a lost-motion connection between an arm 65 13 fixed on the other end of said shaft

and a fixed point 14 on the frame 1 of the machine. This connection preferably consists of a rigid link 15 with a short section of chain 16 so that it may drop out of the way in the inoperative position of the 70 platen and serve merely to pull on the arm 13. In other words, the slack in this connection provided by the chain section requires to be taken up before such connection becomes effective as an operating 75 agency, and the arrangement is such that it thus becomes effective only in the latter portion of the platen's travel, in other words just before such platen reaches its final operative position.

80 In order to prevent the guard frame 4 from too forcibly striking the supporting frame 8 or the platen when it is restored to its folded condition by the action of the coil spring 12, I provide a pair of stops 17 on the end members of said first named frame which are adapted to engage the arms 6 as shown in Fig. 1 in such folded condition of parts.

85 The operation of the above described mechanism should be readily apparent without further explanation. Briefly stated, as the platen moves with a more or less oscillatory movement from the position shown in Fig. 1 to that shown in Fig. 2, the connection made up of link 15 and chain 16 becomes taut, and thereupon the shaft 7 is rocked through a certain angle, thereby bodily throwing the frame upwardly, such frame being at the same time oscillated about its 90 pivotal connection with the arms 6 so that it assumes the upstanding position shown in Fig. 2. This position, it will be understood, is assumed before the bed of the 95 machine closes down on the platen so that the operator, if he has carelessly left his hand between these two parts too long, will have such hand forcibly withdrawn by the action of the guard striking his arm. Moreover, once such guard is raised, owing to the 100 imperforate screen 5, he cannot readily stick his hand back between the platen and bed, and so further endanger himself.

105 The modification in construction illustrated in Figs. 4, 5 and 6 relates wholly to the means provided for operating, that is for oscillating, the rock shaft, which supports and actuates the guard proper. Accordingly, any description of the guard and 110 shaft, with their appurtenant parts, is unnecessary in this connection. In place, however, of a flexible link connection, such as previously described, connecting the arm 13 on the rock-shaft 7 with a fixed point 14 on the main frame 8, a somewhat modified 115 form of link connection is utilized which connects such arm with a movable member, the latter being moved incidentally to movement of the bed of the press instead of incidentally to movement of the platen. The 120

member in question consists of a lever 18 having its lower end pivoted to the main frame about a pin 19. The connection between the upper end of this bar and said arm 13 comprises, in addition to a chain section 20, corresponding to chain section 16, an extensible link made up of two relatively slidable parts 21 and 22, between which is interposed a compression spring 23 so that after the connection as a whole has been drawn taut by oscillation of the lever, the latter may still have a further limited range of movement. For thus moving said lever, a bar 24 is connected at its one end thereto at a point intermediate between such lever's ends, said bar being slidably supported on a roller-guide 25, and having its other end disposed to be engaged by the bed, as the latter swings toward the platen. Since there may be some slight differences in the bed, I preferably fit a set screw 26 in the adjacent end of said bar 24 so as to provide an adjustable stop, as it were, against which the bed will come into contact. In the operation of this modified form of my device, it will be observed that the platen may assume its final operative position without the guard frame 4 being actuated at all, such actuation being timed to occur incidentally to the final closing movement of the bed of the press, or such operation may be made a two-stage one, part being derived from the movement of the platen, and the remainder from the movement of the bed. Where such two-stage effect is desired, all that is necessary is that the lever 18 be held against oscillation to the left so as to constitute of its upper end a temporarily fixed point of attachment for the link connection. By reason of the intermediate position of the spring 23, provision may be made for the raising of the guard frame to its full height before the bed has entirely closed, although this is really unnecessary, since it can be raised to a sufficient height long enough prior to such closure to insure the withdrawal of the operator's hand.

Neither of the two constructional forms of my device herein illustrated and described involve any complex mechanism or modification in the construction of the printing presses to which they are more especially designed to be attached. Moreover, operation of the device may obviously be derived from movement either of the member on which it is supported (the platen in the case in hand), as shown in Figs. 1 and 2, or from the other moving member which co-operates with such first member, such other member being the bed in the present instance, or from both of said members. It is thus accordingly made possible to time the operation of the guard so as to leave the operator as much time as possible for manipulation of the article which is to be gripped between said moving members, and yet insure safety

against accident. It will be understood, of course, that the aforesaid platen and bed may be considered typical of relatively moving jaws in any type of machine, whether printing press or not, between which an operator may be liable to leave or place his hands incidentally to the operation of the machine. Accordingly, I do not regard my invention as limited in its field of usefulness to printing presses merely, although it is particularly adaptable for such use.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a safety device for a machine having two jaws, one movable relatively to the other, the combination of a rock-shaft mounted on one such jaw; a guard pivotally attached to said shaft eccentrically of the latter's axis; a link connecting said guard with a point fixed relatively to said shaft; and means adapted to rock said shaft.

2. In a safety device for a machine having two jaws, one movable relatively to the other, the combination of a rock-shaft mounted on one such jaw; a guard pivotally attached to said shaft eccentrically of the latter's axis; a link connecting said guard with a point fixed relatively to said shaft; and means adapted to rock said shaft including an arm on said shaft and a lost-motion connection between said arm and a relatively fixed point on said machine.

3. In a safety device for a machine having two jaws, one movable relatively to the other, the combination of a rock-shaft mounted on one such jaw; a guard pivotally attached to said shaft eccentrically of the latter's axis; a link connecting said guard with a point fixed relatively to said shaft; and means adapted to rock said shaft including an arm on said shaft and a flexible link connecting said arm and a relatively fixed point on said machine.

4. In a safety device for a machine having two jaws, one movable relatively to the other, the combination of a rock-shaft mounted on one such jaw; a guard pivotally attached to said shaft eccentrically of the latter's axis; a link connecting said guard with a point fixed relatively to said shaft; and means adapted to rock said shaft, said means being operable by such movable jaw.

5. In a safety device for a machine having two jaws, one movable relatively to the other, the combination of a rock-shaft mounted on one such jaw; a guard pivotally attached to said shaft eccentrically of

the latter's axis; a link connecting said guard with a point fixed relatively to said shaft; means normally positioning said guard; and other means, operable by such 5 movable jaw, adapted to rock said shaft against said first-named means.

6. In a safety device for a machine having two jaws, one movable relatively to the other, the combination of a rock-shaft 10 mounted on one such jaw; a guard pivotally attached to said shaft eccentrically of the latter's axis; a link connecting said guard with a point fixed relatively to said shaft; means normally positioning said 15 guard; and other means adapted to rock said shaft against said first-named means, said last-named means including an arm on said shaft and a lost-motion connection between said arm and a relatively fixed point 20 on said machine.

7. In a safety device for a machine having two jaws, one movable relatively to the other, the combination of a rock-shaft 25 mounted on one such jaw; a guard pivotally attached to said shaft eccentrically of the latter's axis; a link connecting said guard with a point fixed relatively to said shaft; means normally positioning said 30 guard; and other means adapted to rock said shaft against said first-named means, said last-named means including an arm on said shaft and a flexible link connecting said arm and a relatively fixed point on said machine.

35 8. In a safety device for a machine having two jaws, one movable relatively to the other, the combination of a rock-shaft mounted on the relatively stationary jaw; a guard pivotally attached to said shaft eccentrically of the latter's axis; a link 40 connecting said guard with a point fixed relatively to said shaft; and means adapted to rock said shaft, said means being operable by said movable jaw.

45 9. In a safety device for a machine having two jaws, one movable relatively to the other, the combination of a rock-shaft mounted on the relatively stationary jaw; a guard pivotally attached to said shaft eccentrically of the latter's axis; a link 50 connecting said guard with a point fixed relatively to said shaft; and means adapted to rock said shaft including an arm on said shaft, a member adapted to be moved by said relatively movable jaw, and a connection 55 between said arm and member.

10. In a safety device for a machine having two jaws, one movable relatively to the other, the combination of a rock-shaft 60 mounted on the relatively stationary jaw; a guard pivotally attached to said shaft eccentrically of the latter's axis; a link connecting said guard with a point fixed relatively to said shaft; and means adapted to rock said shaft including an arm on said 65

shaft, a member adapted to be moved by said relatively movable jaw, and a lost-motion connection between said arm and member.

11. In a safety device for a machine having two jaws, one movable relatively to the other, the combination of a rock-shaft 70 mounted on the relatively stationary jaw; a guard pivotally attached to said shaft eccentrically of the latter's axis; a link connecting said guard with a point fixed relatively to said shaft; and means adapted to rock said shaft including an arm on said shaft, a member adapted to be moved by said relatively movable jaw, and a flexible link connecting said arm and member. 75

12. In a safety device for a machine having two jaws, one movable relatively to the other, the combination of a rock-shaft 80 mounted on the relatively stationary jaw; a guard pivotally attached to said shaft eccentrically of the latter's axis; a link connecting said guard with a point fixed relatively to said shaft; means normally positioning said guard; and other means adapted to rock said shaft against said first-named means, said last-named means including an arm on said shaft, a member adapted to be moved by said relatively movable jaw, and a connection between said arm and member. 85

13. In a safety device for a machine having two jaws, one movable relatively to the other, the combination of a rock-shaft 90 mounted on the relatively stationary jaw; a guard pivotally attached to said shaft eccentrically of the latter's axis; a link connecting said guard with a point fixed relatively to said shaft; means normally positioning said guard; and other means adapted to rock said shaft against said first-named means, said last-named means including an arm on 95 said shaft, a member adapted to be moved by said relatively movable jaw, and a lost-motion connection between said arm and member. 100

14. In a safety device for a machine having two jaws, one movable relatively to the other, the combination of a rock-shaft 110 mounted on the relatively stationary jaw; a guard pivotally attached to said shaft eccentrically of the latter's axis; a link connecting said guard with a point fixed relatively to said shaft; means normally positioning said guard; and other means adapted to rock said shaft against said first-named means, said last-named means including an 115 arm on said shaft, a member adapted to be moved by said relatively movable jaw, and a flexible link connecting said arm and member. 120

15. In a safety device for a machine having two jaws, independently movable relatively to each other, the combination of a rock-shaft 125 mounted on one such jaw; a guard pivotally attached to said shaft eccentrically of the latter's axis; a link connecting 130

said guard with a point fixed relatively to said shaft; and means adapted to rock said shaft incidentally to movement of said jaws.

16. In a safety device for a machine having two jaws, independently movable relatively to each other, the combination of a rock-shaft mounted on one such jaw; a guard pivotally attached to said shaft eccentrically of the latter's axis; a link connecting said guard with a point fixed relatively to said shaft; and means adapted to rock said shaft incidentally to movement of first one, then the other, of said jaws.

17. In a safety device for a machine having two jaws, independently movable relatively to each other, the combination of a rock-shaft mounted on one such jaw; a guard pivotally attached to said shaft eccentrically of the latter's axis; a link connecting said guard with a point fixed relatively to said shaft; and means adapted to rock said shaft incidentally to movement first of the jaw carrying said shaft and then of the other jaw.

18. In a safety device for a machine having two jaws, independently movable relatively to each other, the combination of a rock-shaft mounted on one such jaw; a guard pivotally attached to said shaft eccentrically of the latter's axis; a link connecting said guard with a point fixed relatively to said shaft; means normally positioning said guard; and other means adapted to rock said shaft against said first-named means, said last-named means including an arm on said shaft, an oscillatory lever, a connection between said arm and lever, and a slideable bar connected with said lever to oscillate the same and adapted to be engaged by the other such movable jaw.

19. In a safety device for a machine having two jaws, independently movable relatively to each other, the combination of a rock-shaft mounted on one such jaw; a guard pivotally attached to said shaft eccentrically of the latter's axis; a link connecting said guard with a point fixed relatively to said shaft; means normally positioning said guard; and other means adapted to rock said shaft against said first-named means, said last-named means including an arm on said shaft, an oscillatory lever, a lost-motion connection between said arm and lever, and a slideable bar connected with said lever to oscillate the same and adapted to be engaged by the other such movable jaw.

20. In a safety device for a machine having two jaws, independently movable relatively to each other, the combination of a rock-shaft mounted on one such jaw; a guard pivotally attached to said shaft eccentrically of the latter's axis; a link connecting said guard with a point fixed relatively to said shaft; means normally positioning said guard; and other means adapted to rock said shaft against said first-named means, said last-named means including an arm on said shaft, an oscillatory lever, a connection between said arm and lever, a slideable bar of adjustable length connected with said lever to oscillate the same and adapted to be engaged by the other such movable jaw.

Signed by me this 5th day of March, 1915.

WILLIAM M. REICHART.
